COMBINED LIPSTICK HOLDER AND VANITY CASE OR SIMILAR ARTICLE

Frederick M. Breen, Westchester, N. Y., assignor to Coty,
Inc., New York, N. Y., a corporation of Delaware

Application February 10, 1956, Serial No. 40,114

Term of patent 14 years

(Cl. D86—10)

Fig 1 is a top plan view of a combined lipstick holder and vanity case or similar article showing my new design;

The dominant features of my design reside in the portions shown in full lines.

I claim:

The ornamental design for a combined lipstick holder and vanity case or similar article, substantially as shown and described.
